United States Patent Office.

MARTIN WESSON, OF SPRINGFIELD, MASSACHUSETTS.

Letters Patent No. 74,962, dated February 25, 1868.

IMPROVEMENT IN SHOES.

The Schedule referred to in these Letters Patent and making part of the same.

TO ALL WHOM IT MAY CONCERN:

Be it known that I, MARTIN WESSON, of Springfield, in the county of Hampden, and Commonwealth of Massachusetts, have invented a new and useful Improvement in Shoes; and I do hereby declare that the following is a full, clear, and exact description thereof, reference being had to the accompanying drawings, making a part of this specification, and to the letters of reference marked thereon, in which—

Figure 1 is a perspective view of a shoe with my invention applied.

Figure 2 is a view showing the outside and lining of a portion of a knit or woven web or piece.

Figure 3 is a perspective view of a portion of a woven or knit tubular web, showing outside and lining.

My invention relates to that class of shoes in which the "upper" is made of some woven or knit fabric, and is known as a cloth or carpet shoe, as distinguished from a leather shoe.

The "upper" in shoes of this class is generally composed of the "vamp," which extends backward from the toe, and the "quarter," which encircles the heel and extends forward, and is connected to the vamp. Such quarter has an outside portion and a separate lining, which is much cheaper material than the outside, the upper edges of this outside and lining being united by binding, or by sewing without a separate binding, and the lower edges sewed into the sole. The vamp is sometimes lined, and is also used of single thickness and without a lining.

My invention consists in the construction of a shoe whereof the quarter and the vamp, or either of them, are made of a web or piece which is woven or knit of the proper width to form the said outside and lining in one piece, without any considerable waste of material, and with a saving of expense, and a great improvement in the manufactured shoe.

In the weaving of the web for the purpose specified, I employ a loom, constructed for the weaving of narrow goods, and so arranged that I can weave one portion of the width (about one-half) of any desired ornamented pattern, and the remainder of the width of a much plainer and simpler pattern, one portion being designed for the exterior of the shoe, and the plainer and cheaper portion for the lining. This web I weave in a tubular form, or, by leaving a selvedge on one side of each portion, I form it in a flat web, still having the outside and lining joined continuously at one edge. I am aware that the two portions might be made of the same texture and appearance, but the increased cost of making the lining portion to equal the ornamented outside, renders it undesirable.

By processes familiar to those skilled in operating fancy looms for narrow goods, the texture of the two portions may be greatly varied in appearance and cost, and to a considerable extent in material, as the warp may be of different stock, and also the interweaving of the filling. The lining portion may also, by an adjustment of the loom, be tied at regular intervals to the outside portion, by throwing up certain threads of its proper warp, to engage with the filling of the outside, or the reverse process, while it will still remain separate and distinct from the outside, except at the points of interweaving and at the edge or edges. The lining may also be made of such warp, and so woven that a nap can afterwards be raised upon its surface, after the manner of flannel goods, for the purpose of making a soft and warm interior to the shoe.

In the drawings, fig. 1 represents a shoe, in which A is the outside of a web or piece, which is knit in a tubular form, C, representing the inside or lining of the shoe, both of which may be of any desirable figure or pattern. The "quarter" A is connected to the vamp B at D, on the forward part of the shoe, and extends backwards and around the rear part of the shoe, and is connected to the vamp B at a corresponding part upon the other side of the shoe. The vamp B is also knit or woven in a tubular form, and in precisely the same way as is the quarter, and both are cut from the same piece.

Fig. 2 represents a web or piece which is of double thickness, or having an outside and lining, which is woven or knit in the same manner as that represented in fig. 3, with the exception that the inside or lining is tied or interwoven to the outside at intervals *c c c*, which is done in the process of weaving or knitting.

Fig. 3 shows more fully the form of the tubular web or piece, having a figured outside, A, and a plainer and cheaper inside or lining, C.

It is obvious that the quarter may be woven or knit of sufficient thickness, but single, instead of double or tubular, and having a space or pocket into which to insert the counter, in the construction of the shoe, said

space or pocket being formed in the process of weaving or knitting the web or piece without departing from the principle of construction in the manufacture of the shoe hereinbefore described.

I am aware that the weaving or knitting of narrow goods in a single and flat, or double or tubular form, is not new; but, having described my invention,

What I do claim as new, and desire to secure by Letters Patent, is—

As a new article of manufacture, a shoe, the upper whereof is composed of a woven or knit fabric, and having the "quarter" and the "vamp" of such upper, or either of them, formed of a web which is woven or knit of proper width to form the outside and the lining in one piece, whether such web is made tubular or flat, or with the lining attached to the outside by tying or connecting, substantially as specified.

MARTIN WESSON.
